WINDOW

Edward M. Buchach, Milwaukee, Wis., assignor
to Howard Safety Window, Inc., Milwaukee,
Wis.

Application July 15, 1935, Serial No. 31,374

8 Claims. (Cl. 20—49)

This invention appertains to windows of the type shown in the applications for patents of Jesse R. Howard, Serial Nos. 654,214 and 7,399; filed, respectively, January 30, 1933, and February 20, 1935, and is an improvement thereover.

One of the primary objects of the present invention is to provide sliding and swinging sashes for window frames of such a character that the same can be associated with window frames of substantially standard or ordinary structure with the use of a minimum amount of time and labor.

Another object of the invention is the provision of novel guide rails or tracks for receiving the slide plates or supports for the sashes, whereby free sliding movement of the sashes is permitted, and whereby a durable and leak-proof window will be had, the guide rails being of an integral structure, and so constructed as to be fastened to the frame as a single unit on each side thereof for receiving both the upper and lower sashes.

Another prime object of the invention is the provision of novel means for associating the sashes with the slide plates so that the sashes will have free swinging movement thereon, and whereby the sashes can be quickly connected with or entirely disconnected from the slides to permit the bodily removal of the sashes when necessary or desired.

A further object of my invention is to provide novel means for automatically locking the slide plates against sliding movement when the sashes are swung to their open or partly open position, the sashes automatically releasing the slide plates when the sashes are in their closed position, to permit raising and lowering of the sashes with the slide plates.

A further salient object of my invention is the provision of novel means carried by the slide plates for engaging the guide rails, so that the seeping of air and moisture between the slide plates and rails will be eliminated, novel means being also provided for forming a leak-proof connection between the sashes themselves and the guide rails.

A still further object of my invention is to provide an improved window of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed,

and illustrated in the accompanying drawings, in which drawings:

Figure 1 is a longitudinal section through a window constructed in accordance with my invention taken substantially on the line 1—1 of Figure 2, parts of the sashes and guide rails being broken away in rear of the section line to illustrate structural features.

Figure 2 is a fragmentary front elevation of a window constructed in accordance with my invention, with parts thereof broken away and in section.

Figure 3 is an enlarged detailed, horizontal sectional view taken substantially on the line 3—3 of Figure 2.

Figure 4 is a fragmentary edge elevation of one of the sashes.

Figure 5 is a fragmentary, longitudinal section through a lower corner of one of the sashes illustrating the arrangement of the sash pivot carried thereby.

Figure 6 is a fragmentary longitudinal section taken through a window constructed in accordance with my invention, and looking in the opposite direction from Figure 1, the sashes being shown swung to their open position for permitting the washing of both faces of the window-panes thereof.

Figure 7 is a side elevation of one of the slide plates, with parts thereof broken away and in section to illustrate the latch carried thereby.

Figure 8 is a detail horizontal section through one of the guide rails or tracks, with the sashes removed.

Figure 9 is a fragmentary front elevation of one of the guide rails or tracks showing the slide plates connected therewith.

Figure 10 is a detail horizontal section through one of the slide plates illustrating the latch, the view being taken substantially on the line 10—10 of Figure 7.

Figure 11 is a detailed horizontal section taken substantially on the line 11—11 of Figure 7.

Referring to the drawings in detail, wherein similar reference characters designate corresponding parts throughout the several views, the letter W generally indicates my improved window, which comprises a frame 15, and upper and lower sashes 16 and 17. The window frame 15 is of substantially conventional construction, and includes the side stiles 18 and 19, the lintel 20, and the sill 21. The sashes 16 and 17 are also of substantially ordinary construction, and the sash 16 includes the side rails 22, the top rail 23, and

the bottom or mid-rail 24. The lower sash 17 includes the side rails 25, the bottom rail 26, and the top or mid-rail 27.

In accordance with my invention I provide 5 novel guide tracks 28. These guide tracks are formed from the desired type of metal, and are either cast or extruded, as may be preferred. These rails are rigidly secured to the side stiles 18 and 19 of the window frame in any desired way, 10 and extend from the sill 21 to the lintel 20. By providing these rails I eliminate the usual stop and parting beads, but finishing strips can be utilized, as shown in Figure 3 of the drawings. Each guide rail includes spaced, parallel longitudinally extending channel portions 29 and 30 15 for receiving the slide plates 31 and 32 for the upper and lower sashes 16 and 17. The channels 29 and 30 are connected by an integral bridge or web piece 33, and the edges of the bridge piece are 20 extended to provide longitudinally extending guide and stop flanges 34 and 35. The front channel 30 for the bottom sash has its opposite sides provided with inwardly directed, longitudinally extending ribs 36 and 37. 25 The channel 29 has the inner surface of its rear side wall provided with an integral rib 38, which extends in longitudinal alinement with the flange 34. Extending inwardly from the rear side wall of the channel 29 is a longitudinally extending angle-shaped flange 39, and it is to be noted that 30 this flange extends beyond the web 33 and the front rib 37 of the channel 30.

The slide plates 31 and 32 for the upper and lower sashes are of a particular construction, and 35 are shaped to conform to the configuration of the channels so as to have free sliding movement therein. The outer corners of the slide plates are rabbeted, as at 40, to receive the ribs and flanges 36, 37, 38, and 34. The upper ends of all of the 40 slide plates are shaped to detachably receive the lower ends of the sash cords 41, and these sash cords are provided with counter-balancing weights or springs in the ordinary way. The lower ends of all of the slide plates are provided 45 with pivot or bearing openings 42, for a purpose which will be later set forth.

In order to prevent the seeping of air and moisture up the channels 29 and 30 past the slide plates, each of the slide plates adjacent to their 50 opposite ends carry felt pads 43, which frictionally engage the side and rear walls of the channels. The side edges of the upper and lower sashes have rigidly secured thereto longitudinally extending metal wear plates 44. These 55 metal wear plates have their inner edges folded back and then bent to provide guide channels 45, which are disposed in rabbets formed in the inner corners of the sashes.

By referring to Figure 3, it can be seen that 60 when the sashes are in their vertical positions, the ribs 35 and 39 are received within the channels 44, which tend to create a leak-proof construction. In order to further give an air-tight and leak-proof window, longitudinally extending 65 felt strips 46 are placed within the channels 44, and are secured thereby by angle iron strips 47. The angle iron strips are riveted or otherwise secured to the channels 45, and serve to hold the felt strips 46 in intimate contact with the side 70 walls of the channels 29 and 30.

The lower side edges of the sashes 16 and 17 are cut away to provide pockets 47' inwardly of the wear plates 44, and these pockets receive leaf springs 48, which normally abut the inner faces 75 of the wear plates. The leaf springs 48 are se-

cured to the wear plates adjacent to their upper ends, and their lower ends carry outwardly extending pivot pins or pintles 49, which are adapted to extend through openings 50 in the wear plates. Thumb-buttons 51 are formed on the leaf springs 48 intermediate their ends, and these buttons are accessible through openings 52 formed in the wear plates so that the springs can be depressed to move the pivot pins 49 inwardly. 5

The slide plates 31 and 32 are associated with 10 the channels 29 and 30 prior to the placing of the guide tracks in the frame. After the guide tracks are in place the sashes are connected with their slide plates by moving the pivot pins 49 inwardly and placing the sashes in the frame at an angle 15 until the pins register with the bearing openings 42 in the slide plates, at which time the leaf springs 48 can be released. 10

Pivot pins 49 engaging the walls of the bearing 20 openings 42 will allow free swinging movement of 25 the sashes, and hence sashes can be swung to a vertical closed position, or to an open angle position, as may be desired. The upper sash 16 is of a slightly less width than the lower sash 17, and consequently the upper sash can freely swing past 25 the web 33. The wear plates for the sashes have formed thereon, or secured thereto, stop pins 53 above the pivot pins 49, and when the sashes are swung to an open position the pins are adapted to ride through grooves or slots 54 and 55 formed 30 in the guide tracks 28. The slots or grooves 54 are formed in the web 33 so that the stop pin carried by the upper sash can swing therethrough. The slots 55 are formed in the ribs 37 so that the stop pins carried by the lower sash can 35 swing therethrough. The sides of the window frame are provided with grooves 56, and these grooves may be continuations of the slots 55 formed in the guide tracks 28. This allows the stop pins to swing freely past the window frame, 40 and by this arrangement the window sashes can be readily swung bodily into a room, to permit the cleaning of the opposite faces of the windowpanes. This position is clearly shown in Figure 6 45 of the drawings.

To hold the lower sash in a partly swung open angular position for ventilating purposes, the guide tracks 28 have their ribs 37 slotted, as at 57, below the slots 55. The inner faces of the stiles of the window frame are also grooved for 50 the reception of guides 58, which are adapted to receive the stop pins 53. Obviously the sashes can be swung open by sliding the sashes forwardly until the stop pins register with the desired slots in the guide tracks. 55

The slide plates 31 and 32 carry spring-pressed latches 59, and these latches are adapted to snap into the slot 55 or 57, as the case may be, to hold the slide plates against sliding movement when the sashes are in their swung open 60 position. When the sashes are in their vertical position, the stop pins 53 are adapted to engage the latches and move the same inwardly whereby free sliding movement of the plates and sashes is provided. 65

Obviously, the sashes and the window frame can be provided with any desired type of cooperating means for securing the sashes in a tightly closed position. Likewise, the mid-rails of the sashes 70 and the top rail of the upper sash and the bottom rail of the lower sash can be provided with an approved type of weather strip.

From the foregoing description it can be seen 75 that I have provided an exceptionally simple and

desirable type of window embodying sliding and swinging sashes.

Changes in details may be made without departing from the spirit or the scope of the invention, but what I claim as new is:

5. 1. In a window construction, a window frame including side stiles, guide rails secured to the inner faces of the stiles having integrally connected channels, slide plates freely movable in the channels from one end thereof to the other, window sashes pivotally connected to the slide plates, and friction members disposed between the walls of the channel and the slide plates for forming a leak-proof connection therebetween.

10. 2. In a window construction, a window frame having side stiles, guide tracks connected to the inner faces of the stiles provided with spaced channels, slide plates freely movable in the channels from one end thereof to the other, sashes pivotally connected to the slide plates, and felt pads carried by the slide plates adjacent to their opposite ends for frictionally engaging the side and inner walls of the channels to form a leak-proof connection therewith.

15. 3. In a window construction, a window frame including side stiles, guard rails connected to the inner faces of the stiles, each including spaced, longitudinally extending channels and inwardly directed ribs beyond the channels, slide plates freely movable in the channels, window sashes pivotally connected to the lower ends of the side plates, the inner longitudinal edges of the sashes being rabbeted to receive the ribs, and felt strips in the rabbets for frictionally engaging the ribs.

20. 4. In a window construction, a window frame including side stiles, guide tracks secured to the inner faces of the stiles provided with spaced longitudinally extending channels having inwardly directed ribs, slide plates freely movable in the channels, sashes pivotally connected with the lower ends of the slide plates, the ribs having slots therein at spaced points, and rigid stop pins carried by the sashes above the pivot pins movable through the slots into the channels whereby to hold the sashes against swinging movement, and through the slots out of the channels whereby the sashes can be swung to an angular position.

25. 5. In a window construction, a window frame including side stiles, guide tracks secured to the inner faces of the stiles provided with spaced longitudinally extending channels having inwardly directed ribs, slide plates freely movable in the channels, sashes pivotally connected with the lower ends of the slide plates, the ribs having slots therein at spaced points, rigid stop pins carried by the sashes above the pivot pins movable through the slots whereby the sashes can

be swung to an angular position, and spring-pressed latches carried by the slide plates for engaging in said slots when the sashes are in an angular position to hold the sashes and slide plates against sliding movement, said pins being movable through the slots into the channels to hold the sashes against swinging movement when the sashes are in their vertical position.

30. 6. In a window construction, a window frame including side stiles, guide tracks secured to the inner faces of the stiles provided with spaced longitudinally extending channels having inwardly directed ribs, slide plates freely movable in the channels, sashes pivotally connected with the lower ends of the slide plates, the ribs having slots therein at spaced points, rigid stop pins carried by the sashes above the pivot pins movable through the slots out of the channels whereby the sashes can be swung to an angular position, spring-pressed latches carried by the slide plates for engaging in said slots when the sashes are in an angular position, and said pins being movable through the slots and engageable with the latches to remove the same out of the slots when the sashes are in a vertical position and in said channels to hold the sashes against swinging movement when the sashes are in their vertical positions.

35. 7. In a window construction, a unitary guide track for a pair of sashes comprising a pair of spaced longitudinally extending channels, an integral web connecting said channels, both of said channels having their side walls provided with inwardly directed ribs, the ribs of the channels being in the same vertical plane, and another right angularly extending rib for each channel disposed beyond the first mentioned ribs of the channels.

40. 8. In a window construction, a window frame including side stiles, upper and lower sashes for the frame, guide tracks secured to the inner faces of the stiles provided with spaced longitudinally extending channels, slide plates freely movable in the channels, means pivotally connecting the lower ends of the sashes to the lower ends of the slide plates, latch lugs extending laterally from the sides of the sashes above the slide plates, the front walls of the channels having grooves therein, the latch lugs being movable through the grooves when the sashes are in a predetermined raised position to permit the sashes to be swung open, means for holding the slide plates against movement when the sashes are in their swung-open position, the sashes being adapted to rest on the sill of the window frame adjacent to their outer ends with their inner ends in a raised position, when said sashes are in their full swung-open position.

EDWARD M. BUCHACH.
